UNITED STATES PATENT OFFICE.

GEORGE C. LASARES, OF SPRINGFIELD, MASSACHUSETTS.

TOY CANNON.

1,312,698.

Specification of Letters Patent. Patented Aug. 12, 1919.

Application filed August 19, 1918. Serial No. 250,512.

To all whom it may concern:

Be it known that I, GEORGE C. LASARES, a citizen of the United States of America, residing in Springfield, county of Hampden, and State of Massachusetts, have invented a certain new and useful Toy Cannon, of which the following is a specification.

This invention relates to improvements in toy cannons of the type in which a plurality of projectiles are retained in a suitable holder or magazine and with means for propelling the projectiles one by one, in rapid succession, from the lowermost one of the pile. The propelling means comprises a plunger that is operated in one direction by means of a rotatable shaft to which a suitable arm is attached, this arm serving the purpose of retracting the plunger to allow a projectile to fall from the magazine into the bore of the cannon, and, at the same time serves to compress the propelling spring. Suitable means is provided for supporting the cannon comprising wheels which are located on opposite sides of the barrel. The shaft or rod upon which the wheels are located also serves the purpose of an axle for the wheels, and, as a connecting means between the rear supporting part of the cannon and a block which supports the barrel proper.

Referring to the drawings:

Figure 1 is a plan view of the improvement showing the operative mechanism which comprises, in general, a slidable plunger, means for retracting and releasing the plunger and for compressing the propelling spring to eject the projectile;

Fig. 2 is a vertical sectional view on the line 2-2 of Fig. 1, through the axis of the barrel, illustrating the operative parts, the plunger retracting and spring compressing means being in the normal or inoperative position in which the plunger supports the pile of projectiles and the propelling spring is in an expanded condition;

Fig. 3 is a transverse sectional view on the line 3-3 of Fig. 1 looking in the direction of the arrow, and showing the manner of supporting the plurality of projectiles one above the other in the holder;

Fig. 4 is a transverse sectional view on the line 4-4 of Fig. 1, showing the propelling plunger, the vertical slot through the same, the arm in the slot for operating the same; and the vertical opening through the barrel; and

Fig. 5 is a perspective view of the plunger with the angular-shaped member pivotally attached thereto, which receives one end of the propelling spring, the other arm of the member projecting downward below the lower side of the plunger.

Referring to the drawings in detail; 1 designates the base-part of the cannon which rests upon the floor or other support, as indicated at 2. This part is formed with a forwardly projecting portion 3 which enters the notch 4 in the lower side of the block 5. Passing through the portion 3 in the block 5 is a rod 6. This rod serves the double purpose of securing the base part 1 and the block 5 together, and also as an axle or shaft for the supporting wheels 7 of the cannon. The barrel of the cannon is indicated at 8 and is formed with a bore 9. This bore extends into an opening 10 which receives the propelling plunger 11, a detail view of which is shown in Fig. 5. The plunger is formed with the vertical opening 12 therethrough and the forwardly extending part 13 of the plunger which engages the projectile, the outer end portion of which is chamfered or inclined, as indicated at 14. The bored-out part 10 of the barrel extends to the rear end of the barrel 8. This bored out part is closed by means of the block 15, the reduced part 16 of which enters the opening 10. 10' designates a shoulder against which the plunger 11 strikes when a projectile is fired. 11' designates the shoulder on the plunger that engages the shoulder 10'. The block 15 is formed with a bored out recess 17 to receive the propelling spring 18. This block is secured to the base-piece 1 by means of the screw 19 and assists in rigidly retaining the barrel 8 in place.

Pivottally attached to the open end of the plunger 11 is an angular-shaped piece having a rearwardly extending portion or arm 20 and a downwardly extending portion or arm 21. The attaching pivot is indicated at 22 and permits the spring 18 to have free movement during its operation. The rearwardly extending arm 20 receives the forward end of the spring 18 while the part 21 enters the longitudinal opening 23 in the lower part of the barrel 8. The part 21 serves the purpose of preventing the plunger 11 from rotating about its axis and also serves as a guiding device for the backward and forward motion of the plunger. The open-

ing 12 and the opening 23 must always be in register to permit the plunger operating arm on the rotatable shaft to operate, as will be described. Mounted in the upper 5 end of the block 45 is a rotatable operating shaft 24 which is formed on one end with a crank 25. Secured to this shaft or rod in any suitable manner, is a curved plunger operating arm 26 having a curved surface 10 27 which engages the forward end of the portion 21, of the angular-shaped member, as shown in Fig. 2. The curved arm 26 is of such length that it passes completely through the barrel 8 and through the opening 12 of the plunger when the same is operated. When the crank 25 is rotated the curved portion of the arm 26 moves the plunger 11 rearwardly and, at the same time compresses the spring 18. As the tip end 15 20 of the arm 26 leaves the part 21 the plunger is released and the spring recoils. The forward end 13 engages the lowermost one of the pile of projectiles 28, and forcibly expels the same through the bore of the 25 barrel 8. The inclined portion 14 of the part 13 serves the purpose of allowing the projection 13 to pass under the projectile next above, but will prevent its being expelled by the part 13. A weight 30 serves 30 the purpose of moving the remaining projectiles downward as they are expelled. These projectiles are mounted as shown in Fig. 3 in the wire rack 31. This rack is substantially of hairpin formation, the parallel sides of which enter the annular groove 31' in the projectiles, and, the enlarged portion 32 serves to permit the projectiles to be inserted in the rack. The lower end part 33 is separated as shown and enters openings 34 in the barrel.

It will be seen from this construction that the projectiles can be expelled readily by simply rotating the crank to which the arm 26 is attached. During the compression of 45 the spring the lowermost projectile drops into the bore 9 of the barrel, and, when the spring is released the plunger forcibly drives this projectile from the barrel.

It will further be seen that the invention 50 is simple in construction and one that can be easily assembled without unnecessary labor.

It should be noticed that a platform is provided in the bore of the barrel immediately 55 in front of the plunger receiving part of the barrel, and onto which the projectiles fall from the magazine. The lowermost projectile falls onto this platform as the plunger is retracted. The projectile next 60 above rests on the reduced part of the plunger.

It will be observed that the oppositely located curved walls of the elongated and enlarged opening in the barrel at the rear 65 of the bore serve to support the plunger

during its reciprocating movements as clearly shown in the sectional views of Figs. 2 and 4.

What I claim is:

1. A toy cannon comprising, in combination, a base piece, a block having an opening to receive the base-piece, means for securing the same together, wheels for supporting the cannon, said means serving as an axle for attaching the wheels to the cannon, a barrel mounted in the block and secured to the same and to the base piece.

2. A plunger for a toy cannon comprising a member formed with an opening therein, an angular shaped member pivotally secured 80 to the plunger, one arm of the member serving to receive one end of a propelling spring, the other arm serving as a guide for the plunger, said plunger having a propelling end, the propelling end being chamfered for the purpose described.

3. In a toy cannon the combination, with the barrel thereof, a projectile propelling spring, means for supporting the barrel, comprising a base-piece, a block secured 90 thereto, a member secured to the rear end of the barrel and to the base-piece to provide an extension of the barrel and for receiving the propelling spring, said barrel being also secured to the block.

4. In a toy cannon, the combination, a barrel formed with a vertically disposed opening therethrough, and walls adjacent the opening, a projectile expelling plunger in the opening and supported by walls that 100 are adjacent the opening, a propelling spring in the opening, means comprising a member pivotally secured to the plunger and projecting therefrom into said opening, and for guiding the plunger in the opening, said 105 means serving to attach the propelling spring thereto, and means for operating the plunger independent of the spring.

5. A plunger for a toy cannon comprising a member formed with an opening therein 110 to receive a device for moving the plunger, an angular shaped piece secured to the plunger, one arm of the piece serving to receive one end of the plunger operating spring, the other arm serving as a guiding 115 device for the plunger when in use, one end of the plunger serving as a projectile propelling end.

6. A toy cannon comprising, in combination, a barrel formed with a projectile receiving bore and a slot extending through the barrel in the rear of the bore and communicating therewith, said barrel having an axially bored out part also located at the rear of the projectile receiving bore to receive a 125 projectile engaging plunger, the plunger having a slot extending therethrough and arranged in the plane of the slot through the barrel, means for feeding projectiles into the bore of the barrel, means on the plunger to 130

enter the projectile receiving bore of the barrel for propelling the projectiles from the barrel, means for propelling the plunger; means for retracting the plunger comprising 5 an arm rotatable through the slot in the barrel and plunger, whereby when the arm leaves the plunger the same is released and the projectile thrown forward, as described.

7. In a toy cannon, the combination with 10 the barrel thereof, said barrel having a projectile receiving bore, an elongated opening communicating with the bore and having walls adjacent the opening, but of greater diameter, a plunger supported on the walls 15 of the elongated opening and having a projectile engaging portion which operates in the bore, the plunger and elongated opening having registering openings, means operating in the registering openings for retracting 20 the plunger, and means for moving the plunger forward to expel the projectile.

8. A plunger for the purpose specified, comprising two cylindrical shaped portions of different diameters, the larger portion 25 having an open ended slot, an angular shaped piece pivoted in the slot and having two arms, one arm of the piece serving as a guiding element for the plunger and the other arm serving to receive a coiled expelling spring, as described.

9. In a device of the kind described, a barrel, means for supporting the same com-

prising a base-piece the rear portion of which is designed to engage a support, its forward end portion having an opening, a 35 pin passing through the opening, a block having its lower end notched to receive the forward end of the base-piece and openings therein to receive said pin, said block having an upwardly extending portion with an 40 opening to receive the barrel, the base-piece and block being arranged at right angles to each other and the pin serving as an axle for supporting wheels for the device.

10. A support for the barrel of a toy 45 cannon comprising a base-piece having an upwardly extending portion, a block having an opening therethrough to receive the barrel, the rear part of the barrel being secured to the upwardly extending portion 50 of the base piece, the block and base-piece being secured together at lower end of the block and the forward end of the base piece respectively.

11. A plunger for a toy cannon comprising 55 a member formed with an opening therein, an angular shaped member pivotally secured to the plunger, one arm of the member serving to receive one end of a propelling spring, the other arm serving as a 60 guide for the plunger, said plunger having a propelling end, the propelling end being chamfered for the purpose described.

GEORGE C. LASARES.
